UNITED STATES PATENT OFFICE.

CHARLES H. HATFIELD, OF DES MOINES, IOWA.

GAS-FIXTURE.

SPECIFICATION forming part of Letters Patent No. 622,224, dated April 4, 1899.

Application filed March 17, 1898. Serial No. 674,279. (No model.)

To all whom it may concern:

Be it known that I, CHARLES H. HATFIELD, a citizen of the United States of America, and a resident of Des Moines, Polk county, Iowa, have invented certain new and useful Improvements in Gas-Fixtures, of which the following is a specification.

The object of the invention hereinafter described is to provide improved means for generating gas or vapor from gasoline and so burning the same as to produce a white and brilliant light or illumination of high candle-power in proportion to the quantity of oil consumed.

15 The invention consists in the construction, arrangement, and combination of elements hereinafter set forth, pointed out in my claims, and illustrated by the accompanying drawings, in which—

20 Figure 1 is an elevation of the complete device. Fig. 2 is a perspective of the burner-frame detached from the device and from the mantle and chimney. Fig. 3 is a sectional detail view of one of the T's employed in the 25 device. Fig. 4 is a sectional detail view of a portion of the generating-tube. Fig. 5 is a cross-section of the generating-tube.

In the construction of the device as shown 30 the numeral 10 designates a hanger formed with a hook 11 on its upper end, whereby said hanger may be suspended from a ceiling eye, hook, or other supporting device. (Not shown.) An oil tank or reservoir 12 is mounted by its top on and depends from the lower 35 end of the hanger 10. The reservoir is provided with an ingress-port in its top, closed by a screw-cap 13, and a gage-indicating rod 14 is mounted in the reservoir, projects through the top thereof, and is provided with 40 a float on the lower end carried by the oil in the reservoir in a common manner. A supply-pipe 15 is tapped at its upper end in the lower end of the reservoir 12, and the lower end of the supply-pipe is tapped into the upper 45 arm or port of a cross 16. Generators 17 18 are tapped at their inner ends in the lateral arms or ports of the cross 16 and extend horizontally in opposite directions therefrom. The generators 17 18 are provided with stop-cocks 19 20 adjacent to the cross 16, and horizontal coils 21 22 are formed in the central

portions of the pipes of said generators. The generators 17 18 terminate in couplings 23 24, screw-seated on the ends of the pipes thereof, and conically-hollow plugs 25 26, screw-seated in the outer ends of the couplings. The plugs 25 26 are formed with vents at the apices of the cavities therein, through which the vapor produced in the generators is discharged. Needles or bars 27 28, flattened slightly on one side, are mounted in the generator-pipes between the coils therein and the plugs 25 26. The needles are of about the same diameter as the interior of the pipes and are used to lessen the capacity of the 65 pipes for the flow of oil and increase the heating or generating capacity thereof by providing a greater thickness or quantity of metal to receive and retain heat. A solid supporting-rod 29 is tapped at its upper end 70 in the lower arm or port of the cross 16 and depends therefrom. The lower end of the rod 29 is tapped into the lateral arm or port of a T 30 and supports the same. The cavity of the T 30 is filled with plaster-of-paris or 75 similar sealing substance 31, and cushion-tubes 32 33 are tapped at their inner ends into the longitudinal arms or ports of the T and extend horizontally in opposite directions therefrom. T's 34 35 are mounted on the outer 80 ends of the cushion-tubes 32 33, and burner-stems 36 37 are mounted in the lateral ports of said T's and extend upwardly therefrom in alinement with the axes of the coils 21 22. Burner-frames are mounted on the stems 36 37 85 and are constructed as follows: A collar 38 is mounted removably, replaceably, and loosely on the stem, and a base-ring 39 is mounted concentric with the lower end thereof and connected with the collar by angle-irons 40. Supporting-rods 41 42 43 are fixed to and rise from the base-ring 39, and the upper ends of said rods are bent outwardly and downwardly to support a reflector or shade to be mounted thereon. (Not shown.) A top 90 ring 44 is mounted between and supported by the rods 41, 42, and 43. A socket 45 is mounted in and extends inwardly from the base-ring 39, and a set-screw 46 traverses the ring and intersects the opening or seat of the socket. 100 A mantle-stem 47 is adjustably seated in the socket 45 and held by the set-screw therein.

A mantle 48, of the "Welsbach" or similar type, is carried by the loop at the upper end of the stem 47 and depends around the upper end of the collar 38. A chimney 49, of mica, 5 isinglass, or similar material, is mounted within the rings 39 44 and rests upon the angle-irons 40, inclosing the mantle. Vapor-pipes 50 51 are tapped at their inner ends in the T's 34 35, extend horizontally in opposite directions therefrom beyond the vertical planes of the plugs 25 26, are provided with elbows 52 53, whereby they may be turned upwardly, extend vertically to the horizontal planes of said plugs, and terminate in elbows 54 55, opening to and spaced apart from the vented ends of said plugs. The open ends of the elbows 54 55 are of smaller diameter than the pipes 50 51 or the burner-stem, as is desirable to provide sufficient air with the vapor in said 20 pipes, and the spacing apart of the said elbows from the plugs is for the purpose of admitting air to said pipes. The cushion-pipes 32 33 are normally full of air at atmospheric pressure and provide cushions for the flowing 25 vapor to equalize the discharge thereof to the mantle through the burner-stems.

The flow of oil and consequent generation of vapor is controlled by the cocks 19 20 and the first gas or vapor is produced in the generators by extraneous heating means, such as an alcohol-lamp, applied to the coils 21 22.

I claim as my invention—

1. The gas-fixture comprising a hanger, a reservoir suspended on said hanger, a supply-pipe suspended from said reservoir, a cross 35 on said supply-pipe, generators oppositely horizontally extended from said cross, a solid supporting-rod suspended from said cross, a filled T suspended by said rod, cushion-tubes 40 oppositely horizontally extended from said T, burners mounted on the cushion-tubes, and vapor-pipes communicating with the cushion-tubes and burners and terminating adjacent to and in alinement with the generators, the

generators being located above and in alinement with the burners. 45

2. In a gas-fixture, one or more generators each formed with a coil, a conically-hollow terminal plug provided with a vent at the apex of the cavity thereof, and a needle 50 mounted between the plug and coil and flattened on one side.

3. A gas-fixture comprising a hook, a reservoir depending from said hook, a supply-pipe depending from and communicating with 55 said reservoir, a cross on the lower end of said supply-pipe, generators tapped into the laterals of said cross and projecting in horizontal planes oppositely therefrom, stop-cocks in the generators, a supporting-rod depending from the cross, a T with a solid center mounted on the lower end of the supporting-rod, cushion-pipes tapped into the laterals of the T and extending horizontally therefrom parallel with the generators, T's on the extremities of the cushion-pipes, burners on the latter said T's and vapor-pipes communicating with the latter said T's, extending horizontally therefrom and bent upwardly and inwardly with their terminals adjacent to and 70 in alinement with the terminals of the generators.

4. In a gas-fixture, a suspended supply-pipe, lateral generators thereon, vapor-pipes in alinement with and spaced apart from the 75 terminals of the generators, "Welsbach" burners on the vapor-pipes and located below and in alinement with the generators and a partition in and between said vapor-pipes, whereby communication between the vapor-pipes is cut off between the burners. 80

Signed by me, at Des Moines, Iowa, this 8th day of March, 1898.

CHARLES H. HATFIELD.
